(57) **CLAIM**

The ornamental design for a gas lighter, as shown and described.

DESCRIPTION

FIG. 1 is a top plan view of a gas lighter showing my new design;

FIG. 2 is a side view thereof;

FIG. 3 is a bottom view thereof;

FIG. 4 is another side view thereof;

FIG. 5 is an enlarged rear view thereof;

FIG. 6 is an enlarged front view thereof;

FIG. 7 is a top view in a closed position thereof;

FIG. 8 is side view in a closed position thereof;

FIG. 9 is bottom view in a closed position thereof;

FIG. 10 is another side view in a closed position thereof;

FIG. 11 is another front view in a closed position thereof;

FIG. 12 is another back view in a closed position thereof;

FIG. 13 is a perspective view in open position thereof; and,

FIG. 14 is a perspective side view in a closed position thereof.

The broken lines in the drawings are included for the purpose of illustration and form no part of the claimed design.
